(57) **CLAIM**

The ornamental design for a base stand for electronic game machine, as shown and described.

DESCRIPTION

FIG. 1 is a front, top and left perspective view of a base stand for electronic game machine showing a first embodiment of our new design;

FIG. 2 is a rear, bottom and right perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and

FIG. 9 is a reference perspective view showing a state that an electronic game machine is attached onto this base stand.

FIG. 10 is a front, top and left perspective view of a base stand for electronic game machine showing a second embodiment of our new design;

FIG. 11 is a rear, bottom and right perspective view thereof;

FIG. 12 is a front view thereof;

FIG. 13 is a rear view thereof;

FIG. 14 is a left side view thereof;

FIG. 15 is a right side view thereof;

FIG. 16 is a top plan view thereof; and,

FIG. 17 is a bottom plan view thereof.

The broken line showing of an electronic game machine in FIG. 9 is for illustrative purpose only and forms no part of the claimed design.
